UNITED STATES PATENT OFFICE.

WALTER M. AUSTIN, OF SWISSVALE, PENNSYLVANIA.

MECHANISM FOR VARYING THE STROKE OF INTERNAL-COMBUSTION ENGINES.

1,118,521.

Specification of Letters Patent.

Patented Nov. 24, 1914.

Application filed December 30, 1912. Serial No. 739,239.

To all whom it may concern:

Be it known that I, WALTER M. AUSTIN, a citizen of the United States, residing at Swissvale, in the county of Allegheny and State of Pennsylvania, have invented new and useful Improvements in Mechanism for Varying the Stroke of Internal-Combustion Engines, of which the following is a specification.

This invention relates to internal combustion engines of the type in which the combustible fluid mixture is compressed before ignition.

The principal object of my invention is to provide an improved internal combustion engine in which the products of combustion are completely expelled from the working cylinder before the introduction of a fresh charge of combustible mixture and in which an increased expansive effect is secured for a given volume of combustible mixture.

In an internal combustion engine it is highly desirable to thoroughly scavenge the working cylinder of the products of combustion so as to prevent contamination of the fresh charge of combustible mixture which is drawn in on the next stroke of the engine for various reasons well known to those skilled in the art and which therefore need not be enumerated here. By providing a larger effective expansion volume more power is secured from a given charge of fuel.

In the accompanying drawing; Figure 1 is a central vertical section of a six cylinder internal combustion engine embodying my improvements; Fig. 2 a top plan view of the crank shaft therefor; Fig. 3 a section 40 through the crank shaft on the line *a—a* of Fig. 1, looking in the direction of the arrows; Fig. 4 a similar section on the line *b—b* of Fig. 1; Fig. 5 is a similar section on the line *c—c* of Fig. 1; Fig. 6 an end view 45 of the main crank shaft looking at the right hand end; and Fig. 7 a section of the main crank shaft on the line *d—d* of Fig. 1.

The invention is adapted to be employed with internal combustion engines having two or more working cylinders and as an instance of one application of my invention, I have shown and described the same as applied to a six cylinder engine.

As shown in Fig. 1 of the drawing, the usual engine casing 1 is provided having

cylinders 2, 3, 4, 5, 6, and 7 containing the respective pistons 8, 9, 10, 11, 12, and 13, said pistons being connected in the usual manner with the respective connecting rods 14, 15, 16, 17, 18, and 19. A main 60 crank shaft 20 is journaled in bearings in the engine casing 1 and has crank pins 21, 22, 24, and 25 for the respective connecting rods 14, 15, 18, and 19, the connecting rods 16 and 17 being applied to a common 65 crank pin 23. The crank pins 21 and 25 are in axial alinement as also the crank pins 22 and 24, and the pairs of crank pins so formed are spaced 120 degrees apart. Intermediate the crank pins 22 and 70 23 and 24 the crank shaft is provided with bearing members 26 and 27, preferably ball bearings, and said bearing members may either be integral with the crank shaft, as shown, or may be suitably 75 secured thereto. On opposite sides of the bearing members 26 and 27 are elongated bosses 28 which extend from the crank pins 22 and 24 to the crank pin 23 and form with the intermediate bearing member the 80 crank portion for said crank pins, as more clearly shown in Figs. 2 and 7.

The connecting rods are not mounted directly on the main crank shaft but have intermediate auxiliary cranks or eccentrics, the connecting rods 14, 15, 18, and 19 being rotatably mounted on the respective auxiliary cranks 29, 30, 31, and 32 and the connecting rods 16 and 17 being mounted on auxiliary cranks 33 and 34 integrally connected together as shown. 85

The engine is arranged so that the compression and expansion strokes of one engine piston occur simultaneously with the respective exhaust and suction strokes of another piston, so that the pistons may be considered as in pairs. 95

In the six cylinder construction illustrated, the pairs of pistons are as follows, 8 and 13, 9 and 12, and 10 and 11. The 100 middle pair of pistons 10 and 11 have the corresponding auxiliary cranks 33 and 34 integrally connected together with the eccentricity of the cranks arranged substantially 180 degrees apart, the double 105 crank being preferably formed in halves, as shown in Fig. 3, and secured together on the main crank shaft by bolts (not shown). The auxiliary cranks for the other pistons are similarly arranged, but 110

in this case, the cranks are not integrally connected and it is necessary to provide a suitable connecting means between the co-operating auxiliary cranks. For this purpose, I preferably provide gear wheels 35 and 36 formed integral with the respective auxiliary cranks 30 and 31 and adapted to mesh with gear wheels 37 and 38 secured to the opposite ends of a common shaft 39 rotatably mounted in a hole extending longitudinally through the axis of the pin 23, the auxiliary cranks being preferably formed of half sections adapted to fit over the crank pin. It will now be seen that the gear 35 which is integral with the auxiliary crank 30 meshes with the gear 37 carried by the shaft 39, and since the opposite end of the shaft 39 carries gear 38 which meshes with gear 36, integral with the auxiliary crank 31, the two auxiliary cranks 30 and 31 must rotate together as a unit.

Integral with the auxiliary cranks 29 and 32 are gear wheels 40 and 41 adapted to mesh with internal gears 42 and 43 suitably journaled on hubs formed around the main crank shaft bearings in the engine casing. The internal gears are also provided with external gears 44 and 45 adapted to mesh respectively with pinions 46 and 47 secured to a common shaft 48.

As in the case of the middle pair of integrally connected auxiliary cranks 33 and 34, the second pair of auxiliary cranks 30 and 31 are maintained by the gearing connections with the eccentricities of the cranks spaced substantially 180 degrees apart and this is also the case with the auxiliary cranks 29 and 32.

40 In operation, considering only the two middle pistons 10 and 11 and assuming that the piston 10 is making its suction stroke, a charge of combustible mixture is drawn into the cylinder 4. On the up stroke of the piston 10 this charge is compressed and the pressure in cylinder 4 therefore exceeds the pressure in cylinder 5, which is open to the atmosphere, as the piston 11 is making its exhaust stroke.

50 The pressure acting in cylinder 4 on piston 10 causes the rotation of the integrally connected auxiliary cranks 33 and 34, so that the eccentricity of the crank 33 extends downwardly while the eccentricity of crank 34 is moved to its uppermost position. This results in the piston 11 making a stroke substantially to the cylinder head, so that all the gases in cylinder 5 are driven out.

At the end of the compression stroke of piston 10, a clearance space for the compressed charge is left, such as that shown in cylinder 7, and on the next stroke, the compressed charge in cylinder 4 is ignited and as on this stroke, a fresh charge is drawn into cylinder 5 it will be evident

that the greater fluid pressure still obtains in cylinder 4, so that the relative positions of the auxiliary cranks remain the same. The volume in cylinder 4 at the end of the expansion stroke is thus greater than the volume in cylinder 5 at the end of the suction stroke, so that relative to the volume of combustible mixture drawn in, an increased expansion volume is provided. On the next stroke, the mixture in cylinder 5 is compressed, and as the piston 10 is now making its exhaust stroke, the greater fluid pressure exists in cylinder 5, and consequently, the auxiliary cranks 33 and 34 are turned on the main crank pin, so that the eccentricity of auxiliary crank 34 is forced downwardly and the eccentricity of the auxiliary crank 33 is forced to its uppermost position. It will now be clear that the exhaust stroke of each piston is increased, so as to substantially expel all the burnt gases from the cylinder and thus the succeeding fresh charge of combustible mixture is free from contamination due to products of combustion, while the expansion volume is larger than the volume of combustible mixture drawn in. The pair of pistons 9 and 12 will operate in the same manner, by reason of the operative connection between the auxiliary cranks 30 and 31 and likewise the pistons 8 and 13, by reason of the operative connection between the cranks 29 and 32.

The main crank pins are arranged with the co-operating pairs of cranks 120 degrees apart so as to secure the same balance as provided in the usual six cylinder engine and for the same reason I prefer to dispose the pistons as shown; with a middle pair, the second pair with a piston on either side of the middle pair, and the third pair with a piston on one side of each piston on the second pair. If desired, however, the pairs of pistons may all be arranged the same as the middle pair, with the co-operating auxiliary cranks integrally connected together.

The co-operating pairs of auxiliary cranks may be arranged with the eccentricity of the cranks slightly off center, as shown in Fig. 3, to prevent any possibility of the cranks reversing, but I do not consider this as absolutely necessary.

Having now described my invention, what I claim as new and desire to secure by Letters Patent, is:—

1. In an internal combustion engine, the combination with four cylinders, a piston in each cylinder, a crank shaft provided with a central crank pin and a crank pin on each side of the central crank pin, and connecting rods for operatively connecting the two central pistons with the central crank pin, and the other pistons with the corresponding crank pin on either side of the central crank pin, of an eccentric mounted on each of the other crank pins between the con-

necting rod and the crank pin, gears secured to said eccentrics, gears meshing with the eccentric gears, and a shaft mounted in an aperture extending through the central 5 crank pin for connecting said meshing gears.

2. In an internal combustion engine, the combination with a plurality of cylinders, a piston in each cylinder, a crank shaft provided with crank pins, and connecting rods for operatively connecting said pistons to said crank pins, of an eccentric mounted on the outer crank pin at each side, a gear secured to each eccentric, an internal gear 10 meshing with each eccentric gear and carrying an external gear, gears meshing with said external gears, and a shaft for connecting the last mentioned gears.

3. In an internal combustion engine, the combination with a plurality of cylinders and a piston in each cylinder, of a main crank shaft, two integrally connected auxiliary cranks rotatably mounted on the main crank shaft, a connecting rod for operatively connecting each auxiliary crank with one of the pistons, other auxiliary cranks, trains of gearing for operatively connecting the last mentioned cranks in pairs, and a connecting rod for operatively connecting

each of said cranks with one of the remaining pistons. 30

4. In an internal combustion engine, the combination with a plurality of cylinders and a piston in each cylinder, of a main crank shaft, two integrally connected auxiliary cranks rotatably mounted on the main crank shaft, a connecting rod for operatively connecting each auxiliary crank with one of the middle pairs of pistons, an auxiliary crank rotatably mounted on the main 35 crank shaft on opposite sides of the middle pair of auxiliary cranks, gearing for operatively connecting the second pair of auxiliary cranks, a third pair of auxiliary cranks rotatably mounted on the main crank 40 shaft on opposite sides of the second pair of auxiliary cranks, gearing for operatively connecting the auxiliary cranks of the third pair, and a connecting rod for operatively connecting each auxiliary crank of the second and third pairs with a piston of the engine. 45

In testimony whereof I have hereunto set my hand.

WALTER M. AUSTIN.
